UNITED STATES PATENT OFFICE.

GEORGE PAGONIS, OF NEW YORK, N. Y.

ROTARY ENGINE.

Application filed January 10, 1920. Serial No. 350,639.

To all whom it may concern:

Be it known that I, GEORGE PAGONIS, a citizen of the United States, and a resident of the city of New York, borough of Manhattan, in the county and State of New York, have invented a new and Improved Rotary Engine, of which the following is a full, clear, and exact description.

This invention relates to rotary engines or engines in which a rotary piston or rotor is caused to be rotated under the expansive force of steam, compressed air, or the like.

Among the objects of the invention is to provide a construction of the most simple and durable nature and one in which there is provided simple and effective means for reversing the direction of movement of the rotor.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a front elevation of the main portion of the machine with parts in section on the broken line 1—1 of Fig. 5.

Fig. 2 is a vertical sectional detail on the plane corresponding to the line 2—2 of Fig. 5, but with the slide valve in elevated position.

Fig. 3 is a similar view with the slide valve in depressed position and with the valve actuator shifted.

Fig. 4 is a horizontal sectional detail on the line 4—4 of Fig. 2.

Fig. 5 is a vertical longitudinal section on the line 5—5 of Fig. 1.

Fig. 6 is an inside vertical view of the left half of the casing and with the rotor indicated therein.

Fig. 7 is a vertical transverse sectional detail on the line 7—7 of Fig. 5.

Fig. 8 is a vertical sectional detail on the line 8—8 of Fig. 5.

Referring now more specifically to the drawings I show a stator or casing comprising two mating parts 10 and 11 having aligned bearing holes 12 for the shaft 13 upon which the rotor is mounted or with which it is made integral. The rotor com-

prises a central disk or web 14 and a pair of diametrically opposite pistons 15, shown in the form of disks arranged radially of the rotor and lying in planes meeting or coinciding with the axis of the shaft 13. In other words the casing for the disk shaped space at the center comprises what may be termed an annular cylinder, each portion of which is circular in cross section. The two parts of the casing may be secured together by any suitable means such as detachable fasteners 16 passing through marginal flat flanges 17.

Any suitable means may be provided to introduce the expansive motive or power fluid into the casing for action upon the rotor pistons or blades 15 and to control the exhausts of the same from the casing. Co-operating with the casing member 11 are one or more valve casings 18 in each of which is arranged a slide valve 19 having a stem 20 leading inward radially toward the shaft 13. As shown in Fig. 6 I provide from each valve casing four ports 21, 22, 23 and 24. The ports 21 and 23 are inlets, while the ports 22 and 24 are outlets. Also the ports 21 and 22 are arranged at the same distance from the axis of the shaft and are adapted to be opened simultaneously as a result of the movement of the slide valve 19. Likewise the two ports 23 and 24 are to be opened simultaneously at the outward movement of the slide valve. (See Figs. 2 and 3). The ports 21 and 22 may be regarded as a pair and also the valves 23 and 24. The ports of each pair are spaced circumferentially on opposite sides of a groove or seat 25 formed in the casing member 11 for the accommodation of an abutment member 26 slidable through a channel 27 formed in the casing member 10 parallel to the shaft 13.

The means for controlling the position or operation of the abutments 26 includes for each a stem 28 extending beyond the channel 27 parallel to the shaft 13 and having pin and slot connection at 29 with a lever 30 pivoted at 31 upon an arm 32. A circular cam 33 is fixed upon the shaft 13 and includes a plurality of projections 33' each in turn operating upon the inner end of the lever 30 and causing the abutment pertaining thereto to move outward along the channel 27 out of the path of the rotor blades 15 and against the force of any suitably arranged means such as a spring 34 adapted

to automatically cause or tend to cause the abutment to be seated in the seat 25 between the ports of each pair. Thus at each rotation of the shaft each abutment will be 5 moved outward twice, or once for each rotor blade 15. The throw of each cam 33' is so timed as to withdraw the abutment just at the time a blade 15 is passing a seat 25 and then the spring returns the abutment again 10 to its closed position.

The valve actuator 35 is splined to the shaft 13 so as to rotate therewith, but adapted to slide thereon so as to occupy either the position shown in Fig. 5 or any position 15 slightly to the left thereof. The actuator 35 is of a generally cylindrical form but provided with three surface characteristics as follows: a concentric groove 36 for the yoke 37 of a bell crank lever 38 pivoted at 39, and two cam features 40 and 41. The cams 40 are in the nature of projections two in number diametrically opposed. (See Figs. 20 1 and 2). The other cam features 41 are depressed and likewise diametrically opposed to each other.

Each of the valve stems 20 is provided preferably on its inner end with an anti-friction roller 42 which rides upon either 30 cam feature 40 or 41 of the actuator. The bell crank lever 38 constitutes a holder or adjuster for the actuator and operates in a slot 43 formed in a bracket 44 extending forward and upward from a standard 45 fixed to the base 46 of the engine. The 35 front end of the rotor shaft 13 is journaled in a bearing 44' at the upper end of the bracket 44. A tooth 47 projecting into the slot 43 serves to hold the lever 38 either up in the position shown in Figs. 5 and 7 with 40 the valve actuator in position so that the projections 40 co-operate with the rollers 42, or else down in the position of the dot and dash lines of Fig. 5 in which the depressed portion 41 of the actuator is in the 45 plane of the rollers 42. The lever 38 is preferably designed so that by its own elasticity it will remain in the position shown in Fig. 7 so that for it to be shifted the operator must spring the lever out of the 50 notch to release it from the tooth 47.

A spring 48 surrounds each valve stem 20 and serves to hold the roller 42 in constant contact with the actuator. Since the 55 major portion of the path of each roller 42 with respect to the actuator surface is circular the valve 19 is held most of the time in its mid position as shown in Fig. 5 closing all of the ports. When the valve is moved outward by a cam 40 the pair of 60 ports 23 and 24 are opened momentarily, one port of each pair as 21 or 23 may be regarded as the inlet port, while the other port of each pair as 22 or 24 would be the exhaust port. The ports 21 and 23 may 65 be in communication with the same source

of motive fluid such as a pipe 49 common to all of the slide valves and likewise the exhaust ports 22 and 24 may have a common outlet 50.

While I show a plurality of valve casings 70 18 a specific description of construction and operation of each of them may be understood as being applicable to any number.

The operation of this engine may be briefly summarized as follows in view of the foregoing specific description of the mechanism, assuming that the port 21 is an inlet port and the slide valve 19 is down as shown in Fig. 3 uncovering the pair of ports 21 and 22 momentarily. The abutment 26 between 75 these ports will be seated at this time and so the rotor will be moved in a counter clockwise direction as shown in Fig. 6. The motive fluid being admitted between the moving blade 15 and the abutment the previously admitted fluid ahead of the blade 15 will be exhausted through the port 22 of the next valve casing. By the time the blade 15 reaches the seat 25 of the next succeeding abutment such abutment will have 80 been withdrawn by reason of the actuation of the cam 33 and so on continuously throughout all of the valve systems. The operation being effected through the ports 21 and 22 while the other pair of ports will 85 be kept closed while the engine is operated in this same direction. To reverse the direction of rotation of the rotor the lever 38 is actuated to shift the actuator 35 bringing the projections 40 into action as shown in 90 Fig. 2 at which time the other pair of ports 23 and 24 will be made active, but since the inlet port 23 is on the opposite side of the valve casing, circumferentially, from the inlet port 21 the motive fluid will be caused 95 to act in the opposite direction from the same abutment and hence reverse the engine. This reversing action may be accomplished 100 easily without much effort and without previously stopping the operation of the machine. 105

I claim:

1. A rotary engine, comprising a casing having a central disk-shaped cavity, an annular chamber into which leads the said 115 cavity and at one side three radial channels open at their outer end having their inner ends opening into the annular chamber, the said chamber having in its side opposite the channels grooves, a shaft mounted in the 120 casing and projecting from each side thereof, a rotor comprising a disk-shaped member and two oppositely arranged piston blades, said rotor being mounted on the shaft with its disk-shaped member working 125 in the said cavity and its blades in the annular chamber, reciprocating abutments in the channels and adapted to be seated in the grooves of the annular chamber, means for reciprocating the abutments from one end of 130

the shaft, a plurality of valves on the side of the casing opposite the channels, each valve having two inlet and two exhaust ports leading into the annular chamber, an inlet and exhaust port being on each side of a groove thereof, and means for operating the valves from the other end of the shaft.

2. A rotary engine comprising a casing having a central cavity, an annular chamber into which leads the cavity, and at one side radial channels leading from the chamber and having open outer ends, the said chamber having grooves in the sides opposite the channels, a shaft mounted in the casing, a rotor mounted on the shaft and having piston blades working in the chamber, valves on the sides of the casing opposite

the channels for controlling the admission of motive fluid into the annular chamber and exhausting the same, each valve having inlet and exhaust ports on opposite sides of each of the grooves of the chambers, a plurality of sliding abutments in the radial channels and adapted to extend into the annular chamber, said abutments having stems provided at their outer ends with pins, pivoted and spring pressed levers mounted on the casing, each lever being pivoted intermediate of its ends and having one end forked and slotted to straddle a stem of an abutment and engage the pin thereof, and a cam on the shaft and with which the other ends of said levers engage.

GEORGE PAGONIS.
